CARBURETOR

John H. Stresen-Reuter, Golf, Ill., assignor, by
mesne assignments, to Niles-Bement-Pond
Company, West Hartford, Conn., a corporation
of New Jersey

Application October 24, 1945, Serial No. 624,177

8 Claims. (Cl. 261—39)

1

The present invention relates to carburetors for internal combustion engines, especially for carburetors for use in aircraft engines.

In carburetors for internal combustion engines, it is usual to provide some means for measuring the rate of flow of combustion air to the engine, and to provide means responsive to the measured rate of air flow for controlling the fuel flow so as to maintain the fuel-air ratio substantially constant. It is also usual to provide either manual or automatic means, or both, for varying the fuel-air ratio within selected limits.

The density of the usual liquid fuel remains substantially constant, but the density of the air varies with its pressure and temperature. In order to maintain a constant fuel-air ratio, it is necessary to proportion the mass of air flowing per unit time to the mass of fuel flowing per unit time. The variations in the air density make it difficult to measure the mass of air flowing per unit time.

It may be shown, as set forth in detail in my co-pending application, Serial No. 624,179, filed October 24, 1945, that a constant fuel-to-air ratio may be obtained under varying air density conditions, if the ratio between the fuel pressure differential which measures the velocity of the fuel flow and the air pressure differential which measures the rate of air flow is made proportional to the ratio between the air pressure and the air temperature. In other words, a constant fuel-air ratio is maintained if the carburetor is constructed to operate in accordance with the following equation:

$$\frac{P_1 - P_2}{p_1 - p_2} = k \frac{p_1}{t_1} \quad (1)$$

where

p_1 represents the absolute air pressure at the Venturi inlet,

p_2 represents the absolute air pressure at the Venturi throat,

P_1 represents the absolute fuel pressure on the upstream side of the metering restriction,

P_2 represents absolute fuel pressure on the downstream side of the metering restriction,

t_1 represents the absolute temperature of the air at the Venturi entrance, and

k is a constant, depending on the physical characteristics of the air and fuel meters, the temperature and pressure units chosen, and the particular fuel-air ratio selected.

It is an object of the present invention to provide an improved carburetor operating in accordance with the equation set forth above.

2

Another object is to provide a carburetor of the type described in which the air pressure differential produced by a venturi is balanced against the fuel pressure differential across a metering restriction, and in which the mechanical advantage of the balance mechanism is varied by means responsive to the pressure and temperature of the air in the venturi.

Other objects and advantages of my invention will become apparent from a consideration of the appended specification, claims and drawing, in which the single figure represents, somewhat diagrammatically, a carburetor for an internal combustion engine built in accordance with the present invention.

Referring to the drawing, there is shown an air passage 10 thru which air flows from an entrance 12, past a fixed Venturi restriction 14, a throttle 16, and a fuel discharge nozzle 18 to a mixture outlet 20.

A supercharger is commonly used between the mixture outlet 20 and the intake manifold of the engine. In some cases the supercharger is mounted ahead of the entrance 12, or two superchargers may be used, one in each location.

Fuel flowing to the engine comes from a pump provided with means for maintaining a substantially constant discharge pressure and flows thru a conduit 22, a mixture control 24, a jet system 26, an idle valve 28, a fuel regulating valve 30, and a conduit 32 to the discharge nozzle 18.

A metering device 34 controls the fuel regulating valve 30, and thereby determines the rate of flow of fuel to the engine. The metering device 34 includes a casing 36 containing a sealed bellows 38, one end of which is attached to the casing 36. The interior of bellows 38 is connected thru a conduit 40 to a series of impact tubes 42, whose open ends receive the impact of the air entering the carburetor. The interior of casing 36 is connected thru a conduit 44 to the throat of venturi 14. Therefore, it may be seen that the pressure differential established between the entrance and throat of the venturi acts on the bellows 38 in a direction to expand it. The free end of bellows 38 carries a wear plate 46, which engages a roller 48 carried by a shaft 50 on the end of a rod 52. The rod 52 is positioned by a sealed bellows 54, which is evacuated, so that it expands and contracts in accordance with the variations in pressure inside the casing 36.

An extension of shaft 50 passes thru a slot 56 in the end of a lever 58 which is centrally pivoted at 60.

The other end of lever 58 is slotted at 62 to receive a shaft 64 carrying a roller 66. The shaft 64 is positioned by a rod 68 attached to a frame 70. The frame 70 is attached to the free end of a bellows 72 which contains a fluid having an appreciable coefficient of thermal expansion, so that the position of the roller 66 varies with the temperature inside the casing 36.

The casing 36 carries a projection 74 on which are mounted a pair of opposed aligned bellows 76 and 78. The free ends of these bellows are connected by a stem 80 having valves 82 and 84 formed thereon. The interior of bellows 76 is connected thru a conduit 86 to the fuel line at a point downstream from the jet system. The interior of bellows 78 is connected thru a conduit 88 to the fuel line at a point upstream on the jet system. The free end of bellows 78 carries a wear plate 90 which engages roller 66.

The bellows 38 produces a clockwise moment on lever 58. This moment is equal to the force produced by the air pressure differential acting on bellows 38 times the moment arm of that force, which is determined by the pressure in the casing 36, acting thru the bellows 54.

Similarly, the fuel pressure differential across the jet system produces a counterclockwise moment on the lever 58. This moment is measured by the product of the fuel pressure differential which produces the force acting downward on the roller 66 and the moment arm of that force, which is determined by the temperature in the casing, acting thru the bellows 72.

The mixture control 24 includes a disc valve 91 fixed on a rotatable shaft 92. When the valve 91 is in the full line position on the drawing, fuel may flow thru the mixture control unit to the jet system 26 only thru a conduit 94. The valve 91 may be moved by rotation of shaft 92 to the position shown in dotted lines in the drawing, whereupon fuel may flow to the jet system 26 thru conduit 94 and thru another conduit 96. The full line position of disc 91 is known as its "lean" position and the dotted line position is known as its "rich" position. The valve 91 may also be moved to a "cut-off" position in which it prevents the flow of fuel thru either conduit 94 or 96.

Fuel entering the jet system thru the conduit 94 passes thru a jet or restriction 98. This fuel may also pass thru a restriction 100 controlled by a valve 102, which is biased to closed position by a spring 104. Fuel entering the jet system thru conduit 96 passes thru a fixed restriction 106. Fuel passing thru the restrictions 100 and 106 passes thru another fixed restriction 108.

The idle valve 28 may be reciprocated by a lever 109 connected by a link 110 to an arm 112 mounted on the shaft 114 which carries the throttle 16.

The fuel regulating valve 30 includes a diaphragm 116 attached at its center to a valve 118 which is balanced against discharge pressure. Fuel from the jet system 26 enters a chamber 120 under the diaphragm 116. A chamber 122 above the diaphragm 116 is connected thru a conduit 124 to the metering device 34. A spring 126 biases the valve 118 for movement toward closed position.

Operation

When the forces acting on lever 58 are balanced, fuel may flow from the inlet thru a conduit 88 to the interior of bellows 78 and then

past valve 82 thru a passage 128 and past valve 84 to a drain conduit 130. If the opening at valves 82 and 84 are the same size, the pressure in chamber 122 of the fuel regulator 30 is not changed, and the fuel flow remains steady.

If the air flow now increases, which may, for example, be due to an opening movement of the throttle, then the air pressure differential at the venturi increases and, acting thru bellows 38, rotates the lever 58 clockwise. The valve stem 80 is thereby moved upwards, gradually closing the valve 82 and opening valve 84. This allows more fluid to pass out the drain conduit 130 than is supplied by the valve 82, so that the pressure in chamber 122 is reduced, and the valve 118 is opened wider to increase the fuel flow. As the fuel flow increases, the pressure on the downstream side of the jets decreases, and the bellows 76 collapses partially so that the stem 80 moves back toward its original position. When it reaches a position where the system is again in balance a new lower value of pressure is maintained in chamber 122. The new balanced position of the valve stem will not be exactly the same as its previous balanced position, but will be slightly above it in order that valve 82 may be slightly more closed so as to reduce the pressure in passage 128, which is the same as the pressure in chamber 122.

An analogous operation takes place if the air flow decreases except that the valve stem 80 then moves downwardly and the pressure in chamber 122 increases.

If the atmospheric pressure decreases, then a given air pressure differential at the venturi indicates a smaller mass of air flowing thru the venturi than was the case when the atmospheric pressure was higher. This effect is compensated for by the bellows 54. As the atmospheric pressure decreases this bellows moves the roller 48 to the left thereby decreasing the moment arm of the force due to the pressure differential. The clockwise moment acting on lever 58 is thereby compensated for errors in the measurement of the mass air flow due to atmospheric pressure variation.

If the spring rate of the bellows and its internal spring is constant, which may be safely assumed to be true over the required range of bellows travel, then the distance through which the bellows moves in response to a given change in the pressure differential acting on it is in direct proportion to that change in pressure differential. Consequently, the parts may be so designed that the distance between pivot 60 and shaft 58 varies in direct proportion to the atmospheric pressure.

Changes in air temperature, which likewise cause changes in the mass of air flowing for a given value of air pressure differential are compensated by the bellows 72. For example, if the air temperature increases, the bellows 72 expands and increases the moment arm of the fuel pressure differential on the lever 58. This permits a given value of fuel pressure differential to balance a greater air pressure differential than before, so that the higher air pressure differential resulting from the increased air temperature is thereby compensated.

From the foregoing explanation it may be seen that an equation describing the balancing of the moments acting on lever 58 may be written:

$$k(p_1 - p_2) p_1 = (P_1 - P_2) t_1 \quad (2)$$

where the various terms are defined as in Equation 1.

Equation 2 may be rewritten:

$$\frac{P_1 - P_2}{p_1 - p_2} = k \frac{p_1}{t_1} \quad (3)$$

which is the same as Equation 1.

It may be noted that the equations have been written as though bellows 54 responded to p_1 rather than to p_2 . As a matter of fact, either p_1 or p_2 may be used to operate bellows 54. There is an advantage in the use of p_2 , as shown, in that it compensates for variations in the Venturi meter constant which occur with increasing air flows. The advantage gained by using the Venturi throat pressure to compensate the action of a carburetor is more completely described in the copending application of Milton E. Chandler, Serial No. 490,281, filed June 10, 1943, now Patent No. 2,393,144, issued January 15, 1946.

While I have shown a preferred embodiment of my invention other modifications thereof will readily occur to those skilled in the art and I therefore intend my invention to be limited only by the appended claims.

I claim:

1. A carburetor for an internal combustion engine, comprising an air conduit, means associated with said air conduit for producing two unequal pressures whose difference is a measure of the velocity of flow of air therethru, a fuel conduit, a metering restriction in said fuel conduit for regulating the fuel flow in accordance with the fuel pressure differential established thereacross, means for varying said fuel pressure differential to control the fuel flow including a normally balanced lever, means responsive to the difference of said two unequal pressures for applying a first moment to said lever in one direction, means for varying the moment arm of said first moment in accordance with the atmospheric pressure only, means responsive to said fuel pressure differential for applying a second moment to said lever acting in opposition to said first moment, and means for varying the moment arm of said second moment in accordance with the atmospheric temperature only.

2. A carburetor for an internal combustion engine, comprising an air conduit, means associated with said air conduit for producing two unequal pressures whose difference is a measure of the velocity of flow of air therethru, a fuel conduit, a metering restriction in said fuel conduit for regulating the fuel flow in accordance with the fuel pressure differential established thereacross, means for varying said fuel pressure differential to control the fuel flow including a normally balanced lever, means responsive to the product of the atmospheric pressure and the difference of said two unequal pressures for applying a first moment to said lever in one direction, and means, independent of said last mentioned means responsive to the product of the atmospheric temperature and said fuel pressure differential for applying a second moment to said lever acting in opposition to said first moment.

3. A carburetor for an internal combustion engine, comprising an air conduit, means associated with said air conduit for producing two unequal pressures whose difference is a measure of the velocity of flow of air therethru, a fuel conduit, a metering restriction in said fuel conduit for regulating the fuel flow in accordance with the fuel pressure differential established thereacross, means for varying said fuel pressure differential to control the fuel flow including a normally balanced lever, means responsive to the

unbalance of said lever for operating said fuel pressure differential varying means in a sense dependent upon the direction of unbalance of said lever, means responsive to the difference of said

5 two unequal pressures for applying a first moment to said lever in a fuel flow increasing direction, means for varying the moment arm of said first moment directly in accordance with the atmospheric pressure only, means responsive to said fuel pressure differential for applying a second moment to said lever acting in opposition to said moment and means for varying the moment arm of said second moment directly in accordance with the atmospheric temperature only.

4. A carburetor for an internal combustion engine, comprising an air conduit, means associated with said air conduit for producing two unequal pressures whose difference is a measure of the velocity of flow of air therethru, a fuel conduit, a metering restriction in said fuel conduit for regulating the fuel flow in accordance with the fuel pressure differential established thereacross, valve means for varying said fuel pressure differential to control the fuel flow, means for operating said valve means including a normally balanced lever, means responsive to the difference of said two unequal pressures for applying a first moment to said lever in one direction, means for varying the moment arm of said first moment in accordance with the atmospheric pressure, means responsive to said fuel pressure differential for applying a second moment to said lever acting in opposition to said first moment, and means for varying the moment arm of said second moment in accordance with the atmospheric temperature, said two moment applying means and said two moment arm varying means cooperating to balance said lever in accordance with the equation:

$$\frac{P_1 - P_2}{p_1 - p_2} = k \frac{p_1}{t_1}$$

where

45 p_1 represents the air pressure at the Venturi inlet,
 p_2 represents the air pressure at the Venturi throat,
50 P_1 represents the fuel pressure on the upstream side of the metering restriction,
 P_2 represents fuel pressure on the downstream side of the metering restriction,
 t_1 represents the temperature of the air at the
55 Venturi entrance, and
 k is a constant.

5. A carburetor for an internal combustion engine, comprising an air conduit, means associated with said air conduit for producing two unequal pressures whose difference is a measure of the velocity of flow of air therethru, a fuel conduit, a metering restriction in said fuel conduit for regulating the fuel flow in accordance with the fuel pressure differential established thereacross, valve means for varying said fuel pressure differential to control the fuel flow, and mechanical means, including a fixed pivot lever operatively associated with an element responsive to atmospheric temperature and an independent element responsive to atmospheric pressure for operating said valve means in accordance with the equation:

$$\frac{P_1 - P_2}{p_1 - p_2} = k \frac{p_1}{t_1}$$

where
 p_1 represents the air pressure at the Venturi inlet,
 p_2 represents the air pressure at the Venturi throat,
 P_1 represents the fuel pressure on the upstream side of the metering restriction,
 P_2 represents fuel pressure on the downstream side of the metering restriction,
 t_1 represents the temperature of air at the Venturi entrance, and
 k is a constant.

6. A carburetor for an internal combustion engine, comprising an air conduit, means associated with said air conduit for producing two unequal pressures whose difference is a measure of the velocity of flow of air therethru, separate means independently responsive respectively to the temperature and pressure of the air entering said air conduit, a fuel conduit, a metering restriction in said fuel conduit for regulating the fuel flow in accordance with the fuel pressure differential established thereacross, valve means for varying said fuel pressure differential to control the fuel flow, and mechanical balancing means, comprising a lever actuated by the difference between the product of said fuel pressure differential times the temperature of the entering air and the product of a constant times said air pressure differential times the pressure of the entering air, for operating said valve means to vary said fuel pressure differential in a direction to maintain said mechanical means in balance.

7. A carburetor for an internal combustion engine, comprising an air conduit, means associated with said air conduit for producing two unequal pressures whose difference is a measure of the velocity of flow of air therethru, a fuel conduit, a metering restriction in said fuel conduit for regulating the fuel flow in accordance with the fuel pressure differential established thereacross, valve means for varying said fuel pressure differential to control the fuel flow, means for measuring the temperature of the air in said air conduit, means for measuring the pressure of the air in said air conduit, mechanical means, including a fixed pivot lever, for balancing the product of said fuel pressure differential and said temperature against the product of said air pressure differential and said pressure, and means responsive to unbalance of said mechanical means for operating said valve means to vary said fuel pressure differential in a direction to rebalance said mechanical means.

10

8. A carburetor for an internal combustion engine, comprising an air conduit, means associated with said air conduit for producing two unequal pressures whose difference is a measure of the velocity of flow of air therethru, a fuel conduit, a metering restriction in said fuel conduit for regulating the fuel flow in accordance with the fuel pressure differential established thereacross, valve means for varying said fuel pressure differential to control the fuel flow, a normally balanced lever, means responsive to the difference of said two unequal pressures for applying a first moment to said lever in one direction, means for varying the moment arm of said first moment in accordance with the atmospheric pressure, means responsive to said fuel pressure differential for applying a second moment to said lever acting in opposition to said first moment, means for varying the moment arm of said second moment in accordance with the temperature of the air in said air conduit, fluid motor means for operating said valve means, a source of fluid at high pressure, a source of fluid at low pressure, a pilot valve for selectively connecting said sources to said fluid motor means, said pilot valve having a normal position in which no flow takes place between said motor means and either of said sources and being effective upon opposite movements from said normal position to connect said motor means to one or the other of said sources depending upon the direction of such movement, and a connection between said lever and said pilot valve for operating the same in accordance with the unbalance of said lever, said pilot valve being effective upon unbalance of said lever to cause operation of said fluid motor means and said valve means to vary said fuel pressure differential in a direction to rebalance said lever.
